UNITED STATES PATENT OFFICE.

WILLIAM KING RICHARDSON, OF LEAVENWORTH, KANSAS.

PROJECTILE.

1,141,415.

Specification of Letters Patent.

Patented June 1, 1915.

Application filed March 20, 1915. Serial No. 15,773.

To all whom it may concern:

Be it known that I, WILLIAM KING RICHARDSON, citizen of the United States, residing at Leavenworth, in the county of 5 Leavenworth and State of Kansas, have invented certain new and useful Improvements in Projectiles, of which the following is a specification.

- The object of this invention is to produce 10 a long range armor-piercing projectile that may be used in present constructed guns. This object is attained by reducing the atmosphere resistance to the projectile, 1st, by employing a sharp pointed cap, the ogive of 15 said cap being struck on at least a 7 caliber radius, thereby reducing the velocity of displacement of the air, and a consequent conservation of power; 2nd, reducing the cylinder length of the projectile so that length 20 will but slightly exceed the caliber of the gun for three purposes: 1st, to reduce the skin friction which is directly as the surface; 2nd, to conserve the rotary velocity that is impressed upon the projectile by the 25 rifling of the gun in its motion of translation; 3rd, conserving some of the energy of the compressed air enveloping the projectile at its highest velocity flight, which is inversely as the caliber of the shot. As 30 an illustration, the present service rifle bullet, 150 grains, .3" caliber 2,730 velocity ft. seconds, conserves most of the pressure energy that is available to a square base, due to the fact that the bullet travels but 35 a fraction of an inch before the compressed air enveloping the bullet re-expands at the base of the bullet, and before that pressure is dissipated, due to its velocity of expansion.
- 40 The 3rd object of this invention is attained by employing a tapered rear end terminating in a reduced base at right angles to the longitudinal axis of the projectile. Most of the loss in kinetic energy 45 of a projectile in flight at long range heretofore has been due to the construction of the base or rear end, which have generally equaled in area to the cross-sectional area of the cylinder of the projectile.
- 50 There are many important factors to be taken into consideration in the construction of a base or rear end of a projectile in order to utilize the pressure energy of the atmosphere. As many schemes have been devised, and as none of them to date have been 55 generally adopted, for shaping the rear end

of a projectile to reduce loss of kinetic energy, it is evident the shot as a whole was not symmetrical, or the scheme of construction not practical, or could not perform the 60 function. As a means of illustration, if the cap on applicant's projectile be removed it would affect the accuracy of the shot and reduce the range and striking velocity, or if a blunt or square cap be employed the 65 shot would tumble, due to the pressure energy applied at the base and the high resistance at the nose or ogive of the projectile. If the angle is too abrupt, little or no energy is conserved at high velocity, for the 70 rate of flow and expansion of a normal atmosphere at the base of a projectile having a velocity of 2,184 ft. seconds is limited to that velocity. If the cylinder length of the shot is too long, skin friction destroys 75 its rotary velocity and, therefore, its accuracy at long range and an increased tendency to tumble. A reduction of the cylinder length does not necessarily reduce the sectional density of the shot, for weight is 80 added to the shot by both the cap and the tapered rear end. A reduction of the cylinder length of a projectile moves the center of mass nearer to the pivotal point of 85 resistance and rotation and, therefore, a reduced rotary velocity will sustain the shot in stable equilibrium in relation to the trajectory. As an illustration of the effect of friction, a 12" shot, cylinder length 20", weight 870 pounds, fired from a gun having 90 a twist of 1 turn to 25 calibers, and a muzzle velocity of 2,700 ft. seconds will have impressed upon it a rotary energy equal to 95 738,366 ft. pounds, and frictional resistance of the air, due to rotation of the shot in a range of 24,000 yards, will amount to 67,512 ft. pounds.

With these and other objects in view, which will later be pointed out, the invention will be described in connection with the 100 accompanying drawing, in which: Figure 1 is a sectional view of a projectile embodying the invention. In this figure the tapered rear end is integral with the cylinder of the shot. Fig. 2 is a partial sectional view of a 105 projectile showing the rear end of the cylinder of the shot equipped with a removable tapered base.

Referring to Fig. 1, 1 indicates the cylinder of the shot which extends from the bourrelet 2 to the rotating band 3, and but 110 slightly exceeds in length the caliber of the

- shoe. 4 indicates the ogive of the shot proper, struck from a center on a line perpendicular to the axis of the shot and about 2.6 calibers radius.
- 5 indicates a uniform tapered rear end diverging from a line of the cylinder at an angle of $11^{\circ} 18'$ and terminating with a base perpendicular to the axis of the shot and equipped with a base plug, fuse plug
- 10 and vent plate 6 of any usual or preferred style, it being understood the base plug opening is sufficiently large to admit a tool for boring out the shot to desired dimension.
- 15 7 indicates a soft steel cap secured in the usual way to the ogive of the shot. This cap is struck on a 7.5 caliber radius and is designed to displace the air at .186% of the velocity of the fired projectile.
- 20 8 indicates a lubricant recess bored and reamed in the cap 7 to lubricate and ease the point of the shot.
- Referring to Fig. 2, 5^a indicates a thimble forming the base of the shot having inwardly inclined walls extending from a recessed shoulder provided with a left hand thread 9 that engages a corresponding threaded shoulder at the rear end of the cylinder of the shot, the angle of the inclined
- 25 walls being the same as shown in Fig. 1, but terminating in a square base of less diameter. The base of thimble 5^a is provided with a vent 10 and is for the purpose of allowing the gases of combustion from the powder
- 30 chamber to flow into chamber 11 of the thimble at the point of maximum pressure, thereby relieving the gun of from 3,000 to 4,000 pounds pressure per inch, the vent being so designed that the gases will be redis-
- 35 charged in the gun down to a pressure of 500 pounds in excess of the pressure in the bore at the time the projectile leaves the gun. The drawing to scale indicates a 12" shot.
- 40 15 That the retardation in velocity of a fired projectile, due to the resistance of the air, may be understood, I offer the following solution of the several losses of a 12" shot constructed in accordance with my in-
- 45 vention: weight of shot, 870 pounds; cylinder length, 14"; ogive of cap, 7.5 calibers radius; tapered base, $14^{\circ} 2'$ to 6" square base; muzzle velocity, 2,700 ft. seconds; elevation, $12^{\circ} 36'$; time of flight, 33.8 seconds; altitude, 4,593'; range, 24,200 yards; remaining velocity, 1,746 ft. seconds.
- 50 To determine the skin friction.—The cube of the average velocity (2700 plus 1746 divided by 2 equals 2223) equals 10985463567 $\times$ the constant .0135 equals 148303758 $\times$ the coefficient for the velocity .35 equals 51906315. $\times$ time of flight 33.8 seconds equals 1754438447. divided by the density 836 (2223 average velocity $\times$ .186% velocity of displacement of the air due to the arc of the
- 55 ogive equals 413.5 ft. seconds, this velocity square equals 170982 divided by the constant 120500 equals 1.41 pounds pressure as the altitude equals 4593 the average pressure of the air over the trajectory equals 13.08 pounds pressure plus 1.41 equals 14.49 pounds absolute or a density of 836) equals 2098604.6 $\times$ 8.526 ft. the superficial area of the shot subjected to skin friction due to the motion of translation equals 17889023 ft. 70 pounds loss due to skin friction. Loss due to displacement of the air equal to the square of the velocity of displacement 413.5 ft. seconds $\times$ weight of air displaced 3877.4 pounds (113" area of cross-section $\times$ 80 range in ft. 72600 divided by 144 equals 56970 cubic feet $\times$ weight per cubic foot equals .06806 equals 3877.4 pounds) equals 662965606.8 divided by twice acceleration 64.32 equals 10307301 ft. pounds loss due to 85 displacement.
- Loss due to the pressure of the atmosphere.—We will first determine the absolute pressure at the base of the projectile over that area of cross-section perpendicular to 90 the axis of the projectile. A vacuum takes place at this base at all velocities above 2184' seconds, and as the coefficient of reduction equals .196 the projectile travels as many feet in the path of its flight above 95 this velocity as below. Therefore, the pressure will equal for the higher velocity 13.08 pounds per inch; for the lower velocity, i. e., from 2184 ft. seconds to 1746 ft. seconds, the remaining velocity, we have an 100 average velocity of 1965 ft. seconds. Therefore, the absolute pressure over this area for one-half the length of the trajectory equals the square of 1965 $\times$ the atmospheric pressure 13.08 pounds divided by 105 the square of 2184 equal to 10.58854 pounds pressure. To this we add the pressure over the first half of the trajectory, being 13.08, and divided by 2 for a mean average pressure equals 11.83427 pounds pressure per 110 inch. For convenience of the solution we determine this pressure to be $\frac{1}{4}$ as much for the entire area of base of the projectile, or 2.95857 pounds per inch.
- To determine the absolute pressure over 115 the area of cross-section of the beveled portion the sine of the angle equals .2425 $\times$ the average velocity 2223 equals 539.0775 ft. seconds, the velocity flow and expansion of the air, 539.0775 square $\times$ 13.08 and divided by the square of 2184 equals .7969 pounds pressure per inch, and for an average pressure over the entire base of the projectile it will be .597675 pounds; to this we add the pressure due to the square base 120 2.95857, making 3.556245 pounds $\times$ the area of cross-section 113" $\times$ the range in feet equal 29174723 ft. pounds, the loss due to the pressure of the atmosphere.
- 125 Here it is desired to call attention to a 130

properly constructed base. It will be noted the pressure resistance due to the beveled portion is but .7969 pounds per inch, and for a square base at velocity considered it equals 5 11.83427 pounds per inch. We find the sum of the total resistances equal 17889023 skin friction plus 10307301 displacement plus 29174723 pressure loss equals 57371047 ft. pounds; muzzle energy equals 98610071 ft. 10 pounds; energy in remaining velocity equals 41284591 ft. pounds. Loss, 57375480 ft. pounds.

In considering this invention it is to be understood velocities ranging from 3,000 ft. 15 seconds to 1,300 ft. seconds are considered as applicable to the scheme of construction herein given.

It is to be understood the removable tapered base may be constructed without a 20 perpendicular or end wall without departing from the spirit of this invention.

What I claim as new and desire to secure by Letters Patent is:

1. A hollow projectile provided with a 25 cap, a cylindrical portion, and a detachable hollow base whose walls are substantially of the same thickness as the main projectile walls, and having an inwardly inclined wall terminating in a reduced diameter at right 30 angles to the axis of the projectile and hav-

ing a reduced unobstructed opening through its rear wall communicating with the free interior air space of said base.

2. A hollow projectile provided with a cap that has an ogive greater than the ogive 35 of the shot upon which it is mounted, a cylindrical portion that but slightly exceeds in length the caliber of the projectile, and a beveled base.

3. A hollow projectile provided with a 40 cap the ogive of which is struck on at least 6 caliber radius, a cylindrical portion of less diameter than the bourrelet that but slightly exceeds in length the caliber of the projectile, and a beveled base terminating in a 45 reduced diameter.

4. A hollow projectile provided with a sharp pointed cap having a central longitudinal recess of uniform diameter on its inner face to intersect with the hardened point 50 of the shot upon which the cap is mounted, a cylindrical portion that but slightly exceeds in length the caliber of the projectile and less diameter than the bourrelet, and a beveled base. 55

In testimony whereof I affix my signature.

WILLIAM KING RICHARDSON.
